UNITED STATES PATENT OFFICE.

JOSEPH THOMAS, OF ABERDEEN, WASHINGTON.

VAPOR BATH.

1,425,423.

Specification of Letters Patent. Patented Aug. 8, 1922.

Application filed January 5, 1922. Serial No. 527,153.

To all whom it may concern:

Be it known that I, JOSEPH THOMAS, a citizen of the United States, and resident of Aberdeen, in the county of Grays Harbor 5 and State of Washington, have invented a new and Improved Vapor Bath, of which the following is a full, clear, and exact description.

My invention relates to a vapor bath and 10 aims to provide certain new and useful improvements in connection with a device of this character.

It is an object of this invention to provide a device of the type stated which may be 15 utilized in domestic appliance in that it is preferably to be associated with a conventional bath tub and in that it may further utilize the steam inherent in the hot water system associated with an ordinary tub.

20 A further object of my invention is the provision of a device of the character stated in which steam and vapors will be confined, and in which heated elements may be supplemented for the production of additional 25 vapors, which may embody chemical characteristics, the discharge of these vapors being controllable at the will of the operator.

Still another object of this invention is 30 the provision of a vapor bath embodying the characteristics aforementioned, which when not in use may be stored within a relatively confined space, and which when in use will insure of the application of vapors, to all 35 parts of the body, in a most efficacious manner, it being noted, however, that the user's head may remain in the outer atmosphere in the use of my improved device.

Further objects of this invention will become apparent in the annexed specification 40 taken in connection with the drawings which latter illustrate one practical embodiment thereof, and in which;

Figure 1 is a sectional side view of a bath tub showing my improved vapor bath associated therewith.

Figure 2 is a transverse sectional view taken along the line 2—2 and in the direction of the arrows indicated in Figure 1.

Figure 3 is an end view of the hood and 50 showing a detail of construction.

Figure 4 is a plan view of the framework for supporting the hood, and

Figure 5 is a plan view of the supporting slab upon which the patient rests.

55 Referring now more particularly to Figures 1 and 2 it will be seen that the refer-

ence numeral 10 indicates the body of the tub, which in the usual manner is provided with faucets 11 for the introduction of cold and hot water.

However, contrary to the conventional construction it will be noted that I detachably associate a hood with the body of the tub, and this hood preferably includes a body 12 of any desirable flexible material 65 provided with a head opening 13 which is preferably constructed by means of a resilient band 14. Also the body 12 is provided adjacent its edges with a band 15 which may also preferably incorporate resilient qualities so that the edge of the hood may overlap and embrace the bead 16 of the tub 10.

With a view of supporting the hood in the position shown in Figures 1 and 2 I employ a framework of the type indicated in these 75 figures, as well as in Figure 4, and it will be noted that this framework includes in the embodiment illustrated a plurality of arch members 17 having their ends formed to rest upon the upper edge of the tub, these members being retained in this position by means of longitudinally spaced rods 18 attached as at 19 to the arch members, it being further noted that a plurality of pivoted links 20 movably connect the rods 18 one to the other. 85 Also it will be seen that to further steady the device the rods 18 have one of their ends extending outwardly and downwardly as at 21 so that they may overlap and engage the bead of the tub while their opposite ends 90 terminate short of the opening 13, thus permitting the patient's head to be extended through this portion.

To properly support the person to be treated within the tub 10 I employ a stand which 95 may conveniently include supporting legs 22 which supports a slab 23, the latter being formed with a series of openings 24, as in Figure 5 for a purpose hereinafter specified, and also preferably providing a bifurcated 100 end portion 25.

It will thus be obvious that the tub 10 may be filled with hot water and that the hood will retain the vapors emanating from this water within the space in which the patient's 105 body is disposed, the latter reclining upon the slab, 23, and having his head extending through the opening 13. These vapors will also reach the underside of the body incident to the openings 24, it being noted in 110 this connection that the slab 23 is also provided with a cut out portion 26, in its side

edges, thus insuring a maximum contact between the vapors, and the body of the patient disposed upon this slab. Thus the person being treated is free to breath fresh air 5 although the vapors will not escape to any appreciable extent through the openings 13 incident to the provision of the band 14, and it will be obvious that these vapors will exert the usual beneficial result derived from 10 the use of a vapor bath, although the patient will only have to employ the attachment to produce the effect desired.

Finally if it is desired to treat the patient with chemical vapors it will be obvious 15 that this result may be accomplished by providing a receptacle 27, which is supported by the bifurcated portion 25 of the slab 23 and in placing the chemical solution within this receptacle. The vapors to be 20 generated may be produced by the introduction of a suitably heated element, such as a stone 28, into the receptacle, and due to this immersion it will be obvious that the vapors will be generated, which vapors may 25 be conveniently conducted through the conduits 29 and emanate from nozzles 30 positioned at a point adjacent that portion of the body which is to be treated, it being noted that I preferably 30 provide valves 31 to permit of a controlling of this flow.

Thus all of the objects set forth in the preamble of this specification have been 35 accomplished and it will readily be appreciated that numerous modifications of structure might readily be resorted to without in the least departing from the scope of my claims which are—

1. A vapor bath including in combination 40 a tub and a stand adapted to be positioned within said tub, said stand including a slab at one end thereof formed with cutout portions adjacent its side edges, said

slab being formed with a bifurcated end portion, and a receptacle carried by said 45 end portion, said slab and said receptacle being positioned at a substantial distance from the bottom of the tub.

2. A vapor bath including in combination a tub, a stand positioned within said tub, 50 said stand including a slab, a receptacle carried by said slab at one end thereof, said receptacle being adapted to receive a medicant, and heatable elements adapted to be disposed within said receptacle, said slab 55 and said receptacle being positioned at a substantial distance from the bottom of the tub.

3. A vapor bath including in combination a tub, a perforated stand positioned 60 within said tub, said stand including a slab, a receptacle carried by said slab spaced from the bottom of the tub, said receptacle being adapted to receive a medicant, and conduits having one of their ends connected 65 with said receptacle.

4. A vapor bath including in combination a tub, a stand positioned within said tub, said stand including a slab, a receptacle carried by said slab, said receptacle being 70 adapted to receive a medicant, said slab and said receptacle being at an elevated position from the bottom of the tub, and conduits having one of their ends connected 75 with said receptacle, and nozzles secured to the opposite end of said conduits.

5. A vapor bath including in combination a tub, a hood provided with an opening adapted to envelope the upper edge of said tub, and a framework for supporting 80 said hood, said frame including a plurality of arch members having their ends adapted to rest upon the upper edge of said tub, said hood when applied forming a vapor-tight cover for the tub.

JOSEPH THOMAS.
